(57) **CLAIM**

The ornamental design for a multi-purpose bracket, as shown and described.

DESCRIPTION

FIG. 1 is a front perspective view of a multi-purpose bracket;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof;

FIG. 8 is a front perspective view of another embodiment of a multi-purpose bracket;

FIG. 9 is a front view thereof;

FIG. 10 is a rear view thereof;

FIG. 11 is a left view thereof;

FIG. 12 is a right view thereof;

FIG. 13 is a top view thereof; and,

FIG. 14 is a bottom view thereof.

The broken lines showing portions of the multi-purpose bracket form no part of the claimed design.
